William G. Houskeeper
by W. E. Beatty, Atty.

UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed July 20, 1920. Serial No. 397,764.

To all whom it may concern:

Be it known that I, WILLIAM G. Hous-
KEEPER, a citizen of the United States, re-
siding at New York, in the county of New
5 York and State of New York, have invented
certain new and useful Improvements in
Electron-Discharge Devices, of which the
following is a full, clear, concise, and exact
description.

10 This invention relates to electron dis-
charge devices, such as the audion, and per-
tains more especially to the electrode sup-
porting structure and the arrangement of
the lead wires for the electrodes.

15 An object of this invention is to provide
a rugged and compact electrode unit which
is capable of being subjected to high volt-
ages without injury. Another object is to
provide a simple and efficient means of sup-
porting such an electrode unit. A further
20 object is to prevent leakage currents be-
tween the lead-in wires for the various elec-
trodes of a vacuum tube. Still other ob-
jects will be apparent from the detailed de-
scription of the drawings.

25 For convenience this invention will be
illustrated and described in connection with
a tube of the three-electrode type comprising
an anode, a cathode and a control or
30 grid electrode enclosed in a gas tight, pref-
erably evacuated vessel.

35 The electrode unit hereinafter described
in detail as constituting one form of this
invention, comprises a flattened cylindrical
anode supporting at either end a block of
insulating material. The cathode and grid
40 electrodes are located within the anode and
are supported by suitable means fastened
to the blocks of insulating material. The
45 electrode unit comprising the three above
mentioned electrodes is supported in the
tube by having the anode terminate in a
metallic collar which surrounds an inwardly
50 projecting neck of the containing vessel and
which is preferably frictionally held thereto.
Such a structure is very rugged and is
adapted to be employed with high anode-
cathode voltages.

55 In employing such a tube in high voltage
circuits, special precautions are frequently
necessary to prevent discharges or corona
effects between the various lead-in wires for
the electrodes or between one of the wires

and the above mentioned supporting collar
and also to prevent appreciable leakage cur-
rents through the glass located between the
lead-in wires due to high frequency poten-
tial differences therebetween. These del-
eterious effects may be prevented by sur-
rounding one or more of the lead-in wires 60
by evacuated glass tubes in a manner here-
inafter described in detail.

This invention will be better understood
by reference to the following detailed de-
scription taken in connection with the ac-
companying drawings in which Fig. 1 rep-
resents a vacuum tube of the three-electrode
type embodying this invention; Fig. 2 rep-
resents a modification of the sealing-in ar-
rangement for the lead-in wires of the tube 70
and Fig. 3 illustrates how the tube of this
invention may be employed in an electric
circuit for amplifying or repeating electric
currents.

The electron discharge device illustrated 75
in Fig. 1 comprises an evacuated container 5
of glass which has an inwardly projecting
neck 6 also of glass. The flattened cylin-
drical anode 7 of the electrode unit of the
device is supported by two T-shaped mem-
bers, 8 and 9, which are fastened to a me-
tallic collar 10 surrounding neck 6. The
collar 10 is maintained in position on neck
6, preferably by friction only. Collar 10
is preferably made crimped in a plurality 85
of places and is fashioned so as to originally
have an effective diameter slightly less than
the diameter of the neck 6. The collar 10
may then be forced on neck 6 so that it is
90 tightly held thereto by friction.

Fastened on opposite sides of anode 7 are
metallic posts 12 and 13 for supporting at
either end of the anode, blocks of insulating
material 14 and 15. The blocks 14 and 15
are preferably made of lavite, since such a
material can be readily machined and freed
of absorbed gases. The use of lavite, how-
ever, in a vacuum tube is not a part of this
invention, but is described and claimed in a
copending application of William A. Knoop, 100
filed April 18, 1919, Serial No. 290,968.

Within the anode 7 is located a double
M-shaped filament 17 supported at one end
by wires 18 and by wires 19 at the other
end. Wires 19 are preferably rigidly set in 105
the lavite block 15, while wires 18 pass up

through apertures in block 14 and are resiliently supported by springs 20. This manner of resiliently supporting a filament is not a part of this invention, but is described and claimed in a copending application of Paul A. Watrous, filed November 25, 1919, Serial No. 340,455.

The control or grid electrode for the device comprises a helical wire 25 which is 10 welded at a plurality of points to a plurality of wires 26, 27, 28 and 29. Upright wires 26 and 28 are rigidly connected at their lower ends to insulating block 15; at their upper ends, wires 26 and 28 pass loosely 15 through apertures in block 14 so as to allow the expansion of the grid electrode due to heat. Upright wires 27 and 29 are preferably not fastened to either of the blocks 14 or 15 since it is generally found sufficient to 20 fasten only two of the vertical grid wires to the insulating blocks.

External connections for the anode, cathode and grid are provided by the lead-in wires 30, 31, 32 and 33, lead-in wire 30 being 25 connected to the grid, wire 31 being connected to the two ends and wire 32 to the midpoint of the double M-shaped filament and wire 33 being connected to the anode. It is to be noted that wire 30 is not 30 sealed in the glass at the point 35 of the neck as is the usual practice, but instead is sealed in the glass at the lower end of an evacuated tube 36, the other end of which is sealed to the point 35 of the neck of the tube. Lead-in wire 30 is therefore surrounded by a 35 vacuum from the point 35 to point 37. The lead-in wire 33 for the anode is similarly sealed in at the lower end 40 of an evacuated tube 41, the upper end of which is sealed to 40 the point 42 of the neck 6. Such an arrangement increases enormously the distance along the glass between the points where the lead-in wires 30 and 33 are sealed in the glass with respect to the sealing-in point for 45 the cathode. Leakage currents between the various lead-in wires by means of these evacuated tubes is therefore reduced to a negligible value on account of the long leakage path between the sealing points of the lead-in wires. The provision of the evacuated tubes 36 and 41 also aids in preventing arcing or other discharges between the portion 50 of the lead-in wires enclosed or surrounded by the neck 6. In order to aid in insulating the filament lead-in wires 31 and 32 from the other lead-in wires of the tube it is frequently found convenient to surround the wires 31 and 32 by glass tubes 45 and 46 which, however, need not necessarily be 55 evacuated. Similarly, glass tubes 47 and 48 may be placed on lead-in wires 30 and 33 at their lower ends for aiding in the insulation of these two wires from the filament lead-in wires.

60 65 Another way in which leakage currents

between the sealing-in points of the lead-in wires may be reduced to negligible value is shown in Fig. 2. In this modification the two filament lead-in wires 31 and 32 are surrounded by an evacuated tube 50 to which the lead-in wires are sealed only at the lower end 51. Similarly the grid lead-in wire 30 is enclosed in an evacuated tube 52 as in Fig. 1. The lead-in wire 33 for the anode in this modification, need not be enclosed in an 70 evacuated tube, since ample protection from leakage currents over the glass and discharges between the lead-in wires is secured by tubes 50 and 52.

One way in which the tube illustrated in 80 Fig. 1 may be employed for repeating electric currents is shown in Fig. 3 in which the tube 5 is shown as having its input terminals connected by a transformer 55 to an incoming line 56, while its output terminals 85 are connected by a transformer 57 to an outgoing line 58. Cathode 17 is heated by a battery 59 while space current for the tube is provided by a source of voltage 60. The source of voltage 60 for the type of tube disclosed in Fig. 1 may safely be as high as 90 2000 volts or more. With such an arrangement tube 5 may be employed for repeating to line 58 amplified currents received by tube 5 from line 56.

95 It is to be understood that the electrode structure above described represents only one form in which applicant's invention may be used and that the above described form may be variously modified without departing in anywise from the spirit of this invention as defined in the appended claims.

100 What is claimed is:

1. An electron discharge device comprising a gas tight vessel having a reentrant integral stem, a metallic collar held to said stem solely by friction, and an electrode supported by said collar.

105 2. An electron discharge device comprising a gas tight vessel having an inwardly projecting neck, a crimped metallic collar on said neck, and an electrode supported by said collar.

110 3. An electron discharge device comprising a gas tight vessel having an inwardly projecting neck, a crimped metallic collar surrounding said neck, an electrode unit in said vessel and a plurality of T-shaped members fastened to said collar for supporting said unit.

115 4. An electron discharge device comprising a cathode, a control electrode, an anode surrounding said cathode and control electrode, a pair of supports carried by said anode out of contact with the major portion of said anode, said pair of supports being located at opposite ends of said anode and means for supporting said cathode and control electrode from said pair of supports.

120 125 5. An electron discharge device compris-

- ing a gas tight vessel having an inwardly projecting neck, an anode supported by said neck, a pair of supports carried by said anode out of contact with the major portion 5 of said anode, said pair of supports being located at opposite ends of said anode, a cathode, a control electrode and supporting means for said cathode carried by each of said pair of supports.
- 10 6. An electron discharge device comprising a gas tight vessel having an inwardly projecting neck, an anode supported by said neck, a pair of supports carried by said anode but out of contact with the major 15 portion of said anode, said pair of supports being located at opposite ends of said anode, a cathode, a control electrode and supporting means for said control electrode engaging each of said pair of supports.
- 20 7. An electron discharge device comprising a containing vessel having an inwardly projecting neck, an anode frictionally supported by said neck, cathode and control electrodes surrounded by said anode, a block 25 of insulating material carried by said anode at either end thereof and supporting means for said control electrode engaging each of said blocks.
8. An electron discharge device comprising 30 a containing vessel having an inwardly projecting neck, an anode supported by a crimped collar surrounding said neck, blocks of insulating material carried by said anode at opposite ends thereof, and cathode 35 and control electrodes supported by said blocks.
- ~ 9. An electrode assembly comprising an anode, cathode and control electrodes surrounded by said anode, a block of insulating 40 material carried by said anode at either end thereof and out of contact with the major portion of said anode and means for supporting said control electrode and said cathode between said blocks.
- 45 10. An electrode assembly comprising an electrode, a block of insulating material supported by said electrode at either end thereof and out of contact with the major portion of said electrode, a second electrode 50 surrounded by said first electrode and means for supporting said second electrode between said blocks.
11. An electron discharge device comprising 55 a gas tight vessel having a stem, a metallic collar surrounding said stem and held thereto by friction only, an electrode supported by said collar, a pair of insulating blocks supported by said electrode and a second electrode spaced between said blocks 60 and supported thereby.
12. An electron discharge device comprising 65 a gas tight vessel having a stem, an electrode supported by said stem, two blocks of insulating material supported by said electrode, said blocks having their greatest 70 dimensions parallel to each other and parallel to a surface of said electrode and a second electrode mounted between said blocks and supported thereby.
13. An electron discharge device comprising 75 a containing vessel having an inwardly projecting neck, a cathode, an anode surrounding said cathode and supported from said neck, a block of insulating material carried by either end of said anode, said blocks having their greatest dimensions parallel to each other and parallel to a surface of said anode, said cathode being mounted between said blocks and supported 80 thereby.
14. An electron discharge device comprising 85 a stem, an anode supported by said stem, a block of insulating material at either end of said anode, said anode having projections passing through apertures in each of said blocks whereby said blocks are fastened to said anode, a cathode, a control electrode and supporting wires for said cathode and control electrode inserted in 90 apertures in each of said blocks.
15. An electron discharge device comprising 95 an evacuated vessel having a stem, an electrode supported by said stem, a tubular member carried by the stem and communicating with the interior of the vessel a lead-in wire for said electrode passing through said stem and sealed in the outer end of said tubular member, said lead-in wire being out of electrical contact with said tubular member except at the sealing-in point. 100
16. An electron discharge device comprising 105 an evacuated vessel having a stem, cathode, control and anode electrodes supported by said stem, lead-in wires for said electrodes passing through said stem, an evacuated tubular member within said stem and surrounding a plurality of said lead-in wires. 110
17. An electron discharge device comprising 115 an evacuated vessel having an inwardly projecting neck, cathode, anode and control electrodes supported by said neck, lead-in wires for said electrodes passing through said neck and an evacuated tubular member of insulating material surrounding the cathode and control electrode lead-in wires. 115
18. An electron discharge device comprising 120 an evacuated vessel having a neck, the interior of said neck being substantially at atmospheric pressure, electrodes in said vessel, lead-in wires within said neck for said electrodes and evacuated tubular members within said neck and surrounding a plurality of said lead-in wires.
19. An electron discharge device comprising 125 an evacuated vessel having an inwardly projecting neck, cathode, anode and control electrodes supported by said neck, lead-in wires for said electrodes passing through said neck and evacuated tubular members of 130

- glass within said neck and surrounding a plurality of said lead-in wires, said tubular members being sealed to said lead-in wires only at that end of each tubular member remote from said electrodes.
20. An electron discharge device comprising an evacuated vessel having a stem, an electrode supported by a collar surrounding said stem, a second electrode cooperating with said first electrode, a lead-in wire for one of said electrodes sealed in said stem, and a tubular member surrounding said lead-in wire for preventing electric discharge effects from said wire, said tubular member being free of electrical conductive material except for said lead-in wire.
21. An electron discharge device comprising an evacuated vessel having an inwardly projecting neck, an anode supported by a metallic collar attached to said neck, a cathode, a lead-in wire for said cathode sealed in said neck, and a tubular member surrounding the portion of said wire adjacent said collar for preventing corona effects between said wire and said collar when high voltages are applied to said anode and cathode, said tubular member being free of electrical con-
- ductive material other than said lead-in wire.
22. An electron discharge device comprising an evacuated vessel having a neck, a plurality of electrodes, lead-in wires sealed in said neck for said electrodes, and a tubular member cooperating with said neck to provide a housing for one of said lead-in wires for preventing discharge effects from the housed lead-in wire, said tubular member being free of electrical conductive material other than said lead-in wire.
23. An electron discharge device comprising a containing vessel having a neck, a collar engaging said neck, and an electrode supported by said collar, said collar having corrugations extending in the direction of its axis for rendering said collar expansible.
24. An electron discharge device comprising a containing vessel having a neck, a normally contracting readily expansible collar adapted to be expanded and slipped over said neck and released to grip the same, and an electrode supported by said collar.

In witness whereof, I hereunto subscribe my name this 14th day of July A. D., 1920.

WILLIAM G. HOUSKEEPER.
